(57) **CLAIM**

The ornamental design for an extendible head flashlight, as shown and described.

DESCRIPTION

FIG. 1 is a front, top, left-side perspective view of an extensible head flashlight showing my new design;

FIG. 2 is front, top, left-side perspective view thereof with the head extended;

FIG. 3 is a bottom perspective view thereof with the head retracted and the key chain omitted; and,

FIG. 4 is a right side perspective view thereof with the key chain broken away.
